SELF-DRAINING SEPARATOR BOWL

Stig Beskow, Stockholm, Sweden, assignor to The
De Laval Separator Company, New York, N. Y.,
a corporation of New Jersey

Application September 14, 1932, Serial No. 633,034
In Sweden September 24, 1931

8 Claims. (Cl. 233—46)

This invention relates to bowls for centrifugal separators and has particular reference to the provision of a bowl which is selfdraining after rotation ceases.

5 The purification of liquids containing large proportions of both heavier and lighter solid matters is effected by means of centrifugal separators, the bowls of which are divided into concentric annular chambers which are connected in series alternately at their tops and bottoms. After the separation is completed a certain amount of liquid remains in the bowl which often, for instance in the purification of volatile scouring liquids, involves great inconvenience 10 when the bowl is taken apart and cleaned. Cleaning in such cases has been effected by blowing a jet of steam through the bowl but the apparatus required for this method is rather complicated and inconvenient.

20 If the bowl is of the selfdraining type at present known, that is, a bowl from which the liquid is drained automatically after rotation has stopped, this inconvenience is in part avoided. However, in this arrangement, in which there 25 are provided holes in the bottom of the bowl near to its axis of rotation, drainage is effected only from the inner annular chambers, whereas the liquid is left in the outer chambers.

In accordance with the present invention all 30 of the concentric annular chambers are connected through openings in the bottom of the bowl to discharge points adjacent the axis of rotation. These channels or openings are separate from each other in one form of the device so that the 35 passages opening into certain chambers have no communication with other chambers but independently lead the drained liquid to the points of discharge.

In another form of the invention particularly 40 designed for use in connection with liquids containing large quantities of impurities which are lighter than the liquids, it is desirable to have the inner chambers empty into the outer ones through suitable openings while discharge from the outer 45 chamber flows inwardly through suitable passages towards the axis of rotation adjacent which it is discharged.

The various objects of the invention relating 50 particularly to details of construction will be apparent from the following description read in conjunction with the accompanying drawings in which:

Fig. 1 is a vertical sectional view through one form of separator embodying the invention;

55 Fig. 2 is an enlarged vertical sectional view

taken on a plane through the bowl at an angle with the plane of the section of Fig. 1; and,

Fig. 3 is a vertical sectional view showing a modified arrangement embodying the principles of the invention.

Referring first to Figs. 1 and 2, there is indicated at 2 the lower cup member of the bowl which is provided with a cover 4 of the usual type. Suitable annular partition walls separate the interior of the bowl into annular chambers 10 6, 8 and 10. A conical partition member 12 separates the incoming liquid from the discharge for the heavier components. The inflowing liquid enters at 14 and the heavier liquid is discharged at 16 during the operation of the separator. Located in the bottom of the bowl is a disc 18 which is made separate so as to facilitate cleaning. A plurality of channels 20 are formed in the upper surface of the disc 18 to provide communication between the chambers 8 and 10 as indicated in Fig. 2. Communication between chambers 6 and 8 is established through openings 22 located in the lower portion of the cylindrical wall between these chambers. In the lower surface of the disc 18 are provided radially extending 25 channels 24 which provide passages between the chamber 10 and an annular opening 26 formed by a circular groove in the bottom of the disc 18. Discharge from the channel 26 takes place 30 inwardly towards the axis of rotation through one or more passages 28. An upwardly extending passage 30 furnishes an auxiliary discharge from the lower portion of the annular chamber 6.

The bowl just described is particularly designed 35 for use in connection with liquids containing great quantities of impurities which are lighter than the liquid as, for example, trichlorethylene. In the case of this form of bowl the liquid from the chamber 6 drains into the chamber 8, the liquid then passing from the chamber 8 into the outer 40 chamber 10 from which it flows inwardly through the passages 24 to the discharge. By the use of this arrangement clogging is prevented. It is also found desirable to form the channels at 24 45 of small cross sectional area. The annular channel 26 forms an enlarged continuation of these restricted channels. In the arrangement illustrated, a water outlet is provided at 30. By the arrangement here adopted clogging of the water outlet is very effectively prevented.

50 It may be pointed out that in the arrangement illustrated, the flow of liquid is such that the inner chamber 6 does not receive any substantial amount of flow after being initially filled. That is, the flow takes place downwardly through the 55

chamber 8 and then upwardly through 10, heavier liquid being discharged at 16.

In the embodiment of the invention illustrated in Fig. 3, the chambers are designated 32, 34, 36, 5 38, 40 and 42, being separated by cylindrical walls through which alternate communication is provided as indicated at 46 and 48 through their bottoms and tops respectively. The walls extend between the top disc 43 which provides 10 an outlet passage 44 between it and the cover of the bowl and a separate disc 50 which includes two separate series of channels 52 and 54, the former opening into the chambers 36 and 38 and the latter into the chambers 40 and 42 while 15 not communicating at all with the chambers 36 and 38. 32 and 34 are in free communication with each other, the former being in direct communication with the discharge passage 56 which is located close to the axis of rotation. If the 20 bowl has been stopped, the liquid contained in the various chambers will flow through the respective passages 52 and 54 into the innermost chamber from which discharge will take place at 56.

25 In both the modifications described the channels may be provided in the bowl bottom proper rather than in separate discs although the separate discs are preferred, inasmuch as cleaning is greatly facilitated by their removal. Any 30 number of channels may of course be provided.

What I claim and desire to protect by Letters Patent is:

1. A separator bowl having a number of concentric chambers and means allowing discharge 35 of separated constituents therefrom during centrifugation, two adjacent chambers having an opening at their lower ends affording means for the passage of material to be purified from one chamber to the other, the bottom part of the 40 bowl having a drainage passage extending toward the axis of the bowl and communicating with one of said adjacent chambers and discharging nearer the axis of rotation than does any discharge for separated constituents, whereby both of said adjacent chambers are rendered 45 self-draining.

2. A self-draining separator bowl having concentric annular chambers and means allowing discharge of separated constituents therefrom and independent, substantially radial drainage 50 passages leading from independent chambers toward the center of the bowl, and means insuring that all liquid flowing through said passages shall, before escaping, pass nearer to the center of the bowl than any discharge outlet for separated constituents.

3. A self-draining bowl having concentric annular chambers and means allowing discharge 55 of separated constituents therefrom during centrifugation and means, independent of said discharge means, to drain all the chambers when

the bowl comes to rest, including passages leading from certain chambers, and other passages, independent of the first named passages, leading from certain other chambers, toward the center of the bowl.

4. A self-draining separator bowl having concentric annular chambers and means allowing discharge of separated constituents from the bowl during centrifugation, and drainage passages in the bottom of the bowl into which the 10 contents of all said chambers are adapted to drain, said drainage passages discharging nearer the axis of rotation than does any discharge for separated constituents so that said drainage passages are operative to drain only after the 15 normal centrifugal separating operation of the bowl ceases.

5. A self-draining separator bowl having concentric annular chambers and means allowing discharge of separated constituents therefrom 20 during centrifugation, and drainage passages in the bottom of the bowl communicating with all the chambers and discharging nearer the axis of rotation than does any discharge for separated constituents, the passages opening into certain 25 chambers having no communication with other chambers.

6. A self-draining separator bowl having concentric annular chambers and means allowing discharge of separate constituents from the bowl 30 during centrifugation, a separate lower disc in the bottom of the bowl having drainage passages communicating with said chambers and into which the contents of all said chambers are adapted to drain, said drainage passages discharging nearer the axis of rotation than does any discharge for separated constituents.

7. A self-draining separator bowl having concentric annular chambers and means allowing discharge of separated constituents therefrom 40 during centrifugation, a drainage opening providing communication between an inner and an outer chamber, and a drainage passage opening into said outer chamber and discharging nearer the axis of rotation than does any discharge for 45 separated constituents.

8. A separator bowl having a number of concentric chambers and means allowing discharge of separated constituents from the bowl during centrifugation, two adjacent chambers having 50 an opening at their upper ends affording means for the passage of material from one chamber to the other and drainage passages, independent of said discharge means and opening, communicating with said chambers respectively and into 55 which said chambers are adapted to respectively drain and which discharge nearer the axis of the bowl than does any discharge for separated constituents.
